CLAIM

The ornamental design for a food product, as shown and described.

DESCRIPTION

FIG. 1 is a perspective view of a food product showing our new design;

FIG. 2 is a front elevational view thereof, the undisclosed rear being a mirror image;

FIG. 3 is a side elevational view thereof, it being understood that the opposite side of FIG. 3 is a mirror image;

FIG. 4 is a cross-sectional view thereof, taken along line 4—4 of FIG. 2;

FIG. 5 is a bottom plan view thereof; and,

FIG. 6 is a top plan view thereof.
